CORDLESS ELECTRIC UPRIGHT GRASS SHEAR

William E. Bartasevich, Jr., Glenshaw, and James E. Edgell, Bradford Woods, Pa., assignors to Disston Inc., Pittsburgh, Pa.

Filed July 16, 1973, Ser. No. 379,380

Term of patent 14 years

Int. Cl. D8—03

U.S. Cl. D8—8

FIG. 1 is a perspective view of a cordless electric upright grass shear embodying our new design.

FIG. 2 is a front elevation thereof, with the handle member fragmentarily shown for ease of illustration;

FIG. 3 is a rear elevation view thereof.

FIG. 4 is a side elevation view thereof which is a mirror image of its laterally opposite side.

FIG. 5 is a bottom plan view thereof.

FIG. 6 is a top plan view thereof.

We claim:

The ornamental design for a cordless electric upright grass shear, substantially as shown.
